SELF-ADJUSTING WRENCH OR SIMILAR ARTICLE

John V. Larson, Chicago, Ill.

Application July 13, 1949, Serial No. 3,878

Term of patent 14 years

(Cl. D54—16)

To all whom it may concern:

Be it known that I, John V. Larson, a citizen of the United States and a resident of Chicago, county of Cook, and State of Illinois, have invented a new, original, and ornamental Design for a Self-Adjusting Wrench or Similar Article, of which the following is a specification, reference being had to the accompanying drawing forming part thereof.

In the drawing:

Figure 1 is a perspective view of a self-adjusting wrench, showing my new design;

Figure 2 is a top plan view;

Figure 3 is a bottom plan view; and

Figure 4 is an end view looking into the jaws of the wrench.

I claim:

The ornamental design for a self-adjusting wrench or similar article, substantially as shown.

JOHN V. LARSON.
